UNITED STATES PATENT OFFICE

ROBERT S. PEELE, OF HOLLIS, NEW YORK, ASSIGNOR TO THE PEELE COMPANY, OF BROOKLYN, NEW YORK, A CORPORATION OF NEW YORK

POWER FIXTURE FOR ELEVATOR DOOR OPERATORS

Application filed January 3, 1931. Serial No. 506,483.

My invention relates to a power fixture for elevator door operators, and more particularly to a single unitary structure for application to the guide rail structure in an elevator shaft embodying therein all of the mechanisms essential to the application of power to an elevator door for opening and closing same.

The fixture of the invention was produced for use in connection with a type of operator embodying therein a small motor acting through speed reducing gearing upon a sheave over which the flexible connections, connecting the sections of what is known as "counterbalanced" doors, pass.

In the production of such doors it has long been the practice to assemble the guide rail structure in a plurality of lengths in the shop before shipment for installation in the wall of a shaft. This guide rail structure usually consists of what is known as a "wall angle," one flange of which abuts against the wall of the shaft and is bolted thereto, and the other angle of which projects inwardly of the shaft and has firmly secured thereto a guide rail co-operating with the guide shoes upon the door sections to permit the free sliding movement of the door sections and hold them close to the wall of the shaft about the door openings.

When assembling the different lengths of the guide rail structure in the shop, the wall angle of some of the sections was provided with a plate pierced in a position to properly locate the various sheaves in their relation to the various doors, and expose them upon opposite sides of the wall angle, so that when mounting the doors in the shaft, it was merely necessary to pass the chains or other flexible connections through such openings and about the sheaves and connect the ends thereof to the sections of the door adjacent each sheave.

In the manufacture of the type of operator above referred to, the practice, prior to my invention, was to also mount the motor upon the wall angle after proper adjustment of the gearing connecting the motor to the sheave, all wiring of the motor being done after the installation of the guide rail struc-

ture with the attached motors and sheaves. In some instances, it was the practice to install the motors after the guide rail structure was in position upon the wall of the shaft.

When constructing and installing the operator as above described, there were not only manufacturing difficulties in securing a proper adjustment of the various co-operating parts, but the running of the electric lines and their connections with the various motors was a very troublesome procedure, and one requiring expert skill and familiarity with the peculiar characteristics of the operator installation.

With the above conditions in mind, I have provided a power fixture for elevator door operators in which the motor, the sheave and the transmission gearing are assembled in the shop in a single housing which is so constructed as to not only assure a fixed properly adjusted relation of these parts, but will facilitate such assembly.

With a fixture embodying the invention, a sheave, its operating motor and the transmission gearing may be mounted upon the guide rail structure while in the shop and by a single operation, the construction and arrangement of the housing being such that all of the working parts are so inclosed as to avoid any possible interference of such parts with each other, and to exclude the dust and dirt, which accumulate rapidly in an elevator shaft, from all of these working parts.

The construction of the housing is such that all parts of the fixture may be contained within the space in an elevator shaft available for the installation of the operator, while at the same time facilitating the running of the electric lines for supplying power to the operators of the various doors in a shaft in relation to the motor, and for making the necessary connections between these power lines and the branch lines to the motor, and with the switch mechanisms controlling the flow of the current through these branch lines from the main line through these branch lines to the motor. Furthermore, the construction is such that all of the connections excepting those to the mains may be made during the installation of the fitting in relation

- to the guide rail structure while in the shop. In fact, the fitting includes therein, as an integral part thereof, outlet boxes so located in relation to the motor and to the means of attachment of the fixture to the guide rail structure as to facilitate the running of the main lines through the shaft, and the making of the necessary connections with the main lines after they have been run. The housing construction is such as to not only adequately protect the wiring, to eliminate fire hazard, but to avoid possible interference between the moving parts of the fixture and the various electrical lines adjacent same.
- 15 In addition to the foregoing characteristics, the construction of the housing of the fixture is such that while allowing a free run of the flexible connections, the likelihood of the escape of such connections over the shrouds of the sheave is reduced to a minimum.
- 20 In the fixture of the invention, the various parts are housed in, or connected with, a single metal casting so formed that all such parts, without adjustment, will be brought and maintained in the proper operative relation, and be so protected as to avoid any possible interference of parts or of the electrical wires with the movable parts.
- 25 The invention consists primarily in a power fixture for elevator door operators embodying therein a narrow casing recessed at one edge thereof to form a pocket, having a front opening and a bottom opening, a sheave having a gear attached thereto, means whereby said sheave and gear are mounted in the side walls of said pocket, said gear and sheave projecting through said front opening, a circular recess forming flange upon the other side of said casing, the wall between said recess and said pocket having an opening adjacent the perimeter of said gear, a circular motor in said recess having its shaft projected through said opening, a gear carried by said shaft and enmeshed with the gear upon said sheave, a cap closing said motor recess, and means whereby said casing may be attached to the guide rail structure for elevator doors; and in such other novel characteristics as are hereinafter set forth and described, and more particularly pointed out in the claims hereto appended.

Referring to the drawings,

Fig. 1 is a side view of the fully wired, assembled and installed unit;

Fig. 2 is an edge view thereof from the right of Fig. 1;

Fig. 3 is a plan view thereof;

Fig. 4 is a vertical section on the line 4—4 of Fig. 1;

Fig. 5 is a detail view of the casing from the left of Fig. 1; and

Fig. 6 is a section on the line 6—6 of Fig. 5.

Like numerals refer to like parts throughout the several views.

In the embodiment of the invention shown in the drawings, the guide rail structure is indicated in Figs. 1 and 3 at 10. This guide rail structure not only supports the guide rails along which the door sections have movement, but supports the door sections and all of the working parts thereof. With the particular type of operator to which the present invention relates, a small narrow motor is used, the application of power to this motor being controlled by a switch mechanism also carried by the rail structure adjacent the sill of the door opening, as well as by either car or hall controls, according to the type of elevator installation. The guide rail structure extends inwardly from the wall of the shaft only a few inches, the amount being determined by the thickness or arrangement of the door sections.

The sheave, over which the flexible connections between the door sections run, which connections ordinarily include a link chain, must be located adjacent the inner edge of the guide rail structure in order to permit a proper run of the connections during the opening and closing of the door, and portions of the sheave must be exposed upon opposite sides of the guide rail structure to permit a proper run of the flexible connections to permit their attachment to the door sections.

The fixture of the invention is not only so constructed as to satisfy all of the above conditions required by standard installations of elevator doors, but to ensure a proper, adjusted relation of the various working parts before the guide rail structure is shipped from the factory so as to avoid possibility of an improper installation of the operator, as well as the added expense of installation on the job, and of possible subsequent servicing to correct error arising during installation.

To secure the desired result, I provide a casing 11 which may be an unfinished casting, since precision work is not required. This casing is provided, at one side thereof, with a pocket 12, closed in all respects excepting for a front opening 13 in the casing, and a bottom opening 14 adjacent the back of the casing, which openings are provided for the purpose of permitting a free run of the connecting chains through the pocket and above the sheave 15.

The side walls of the casing forming the pocket are parallel, and the general form of the other wall of the pocket is such as to follow the perimeter of the sheave. The side walls of the pocket have mounted therein suitable bearings, such as 16, for the shaft 17 of the sheave 15, one shroud 18 of which is in the form of a spur gear through which power may be applied to the sheave.

Projecting from the front wall of the casing, above the opening 13, is an arcuate shield 19 following the perimeter of the sheave 18

with the two-fold object of preventing the possibility of the chain jumping one shroud of the sheave, and for excluding dust, dirt and grit from the portion of the sheave projecting through the opening 13 and from the chain passing about said sheave. At one side of said opening and below the shield 19 is a guard flange 20. The relative diameter of the pocket 12 and of the sheave 18, and the relative width of said pocket and of said sheave, are such as to permit the free threading of a chain through the pocket and about the sheave without affording clearance upon either side of the sheave sufficient to receive said chain in the event of its jumping the shroud of the sheave.

It will be noted that the greater part of the sheave is completely enclosed by the walls of the pocket 12, and that the portion of the casing forming this pocket is but little wider than the sheave itself.

Upon the side of the casing opposite to that in which the pocket 12 is formed, is a circular flange 21 forming a recess 22 for the reception of a circular motor of special construction. Adjacent the bottom of this recess the casing is slotted as shown at 23 to permit the passage of the terminal leads of the motor from the recess. The motor is secured in said recess by means of a cupped cap 24 enclosing the portion of the motor projecting beyond the recess. This cap is secured in position by means of screws 25.

The wall of the casing separating the recess 22 from the pocket 12 has an opening 26 therethrough. This opening 26 is co-axial with the recess 22, and located adjacent, but beyond, the perimeter of the sheave 18. The casing and the cap 24 are provided with suitable bearing bosses 27 and 28 for the shaft 29 of the rotor of the motor.

It will be noted that by employing a casing constructed as above described, a suitable support for the sheave and for the motor is not only afforded, but in assembling the sheave and the motor in the casing, no fitting or adjusting is required because the construction and arrangement of the fitting is such as to establish and maintain a proper relation of the motor and the sheave. The shaft 29 of the rotor has formed thereon, or secured thereto, a small driving gear 30 which will be enmeshed with the gear shroud 18 of the sheave 15 as a result of the locating of the motor within the recess 22.

The casing 11 is provided with a flange 31 above the pocket 12 by means of which the casing with its contained sheave and motor may be firmly secured to the guide rail structure 10.

The motor itself is shown at 32.

To facilitate the running of the electric mains and the connections of the motors and switches in relation thereto, I provide in the casing not only means facilitating the run of

the mains, but the connection of such mains with the motor and with branch lines to the motor including therein a rail switch mechanism. The motor 32 is a three-phase motor requiring the running of three main lines throughout the shaft which work can be done only after the installation of the guide rail structure. The motor connections with the switch upon the guide rail structure may, however, be done in the shop so as to reduce the electrical work within the shaft to merely the running of the main lines and the making of three connections therewith.

The casing 11 is so constructed as to not only permit the connection of electrical conduits therewith, but to also provide in the casing, adjacent the recess 22, a junction or outlet box which is conveniently accessible for the purpose of making such electrical connections when the guide rail structure carrying the casing is in the shaft.

The casing 11 is provided at the top thereof with an opening 33 adapted to receive a bushing 34 used in the attachment of a conduit 35 to the casing. Below this opening, the casing is provided with a channel 36. Toward the bottom of this channel an opening 37 leads into a chamber 38 at the bottom of and formed integrally with, the casing 11. In the bottom wall of the chamber 38 are two openings 39 and 40 adapted to receive respectively bushings 41 and 42 by which conduits 43 and 44 may be connected with the bottom of the casing. The conduit 44 at its lower end is connected with a switch box not shown, which switch box is also connected with the section of the guide rail structure 10 upon which the casing 11 is mounted. Consequently, the conduit 44 may be assembled in the rail structure at the same time that the casing 11 is assembled in this structure so that wires may be run through this conduit 44 and electrical connection of these wires with the motor and with the switch may be made in the shop.

The chamber 38 is located in its entirety below the flange 21 and the cap 24 thus affording clearance for the free run of the chain below the pocket 12. The back of the chamber 38 is substantially flush with the top of the cap 24 and so that when the fitting is installed, the back wall comes almost flush against the wall of the shaft. Access to the chamber 38 can, therefore, be had only from the front thereof or from the shaft side. To permit this access, I formed the chamber with an open front and close this front by means of a cover plate 45 removably connected with the casing by means of screws or in any other desired manner.

One side wall 46 of the chamber 38 is extended to a plane parallel with the flange 31, and has openings therethrough for the reception of screw bolts or other means by which the lower portion of the casing 11 may be firmly secured in relation to the guide rail

structure. The closure plate 45 is provided with a hollow extension 47 enclosing said side wall 46, and provided with a throat 48 having a slot therein communicating with the channel 36 through which the wires of the electrical means may be led into the chamber 38.

In the drawings, the three wires constituting the electrical mains are indicated at 49, 50 and 51; the three motor terminals at 52, 53 and 54, and the wires leading to and from the switch box at 55, 56, 57 and 58.

It will be noted that the closure 45 is presented inwardly of the shaft so that no difficulty will be experienced in removing and replacing this closure when making electrical connections.

It will also be noted that the casing 11, except for the cap 24 and the cover 45, is formed of a single casting which will ensure uniformity in the relation of parts as to all fittings produced.

There are two fittings used with each door, and consequently, the fittings will be made right and left. A fitting embodying the invention has the various openings for the bearings of the motor and of the sheave drilled therein, jigs being used to ensure accuracy in the locating of these holes. The sheave is then mounted in the pocket 12, ball bearings preferably being used for this purpose, and the openings in the side walls of the pocket being formed to receive said bearings. The size of the opening 13 is such as to permit the insertion of the sheave through this opening, the shaft for the ball bearings being driven after the sheave is in position.

The stator of the motor 32 is then positioned within the flange 21, and firmly secured in relation to said flange. The rotor with its shaft is then mounted within the field stator, the gear 30 being passed through the opening 26, as shown more particularly in Fig. 2, and enmeshed with the gear shroud 18. The cap 24 is then secured in relation to the casing 11.

When mounting the stator of the motor within the recess formed by the flange 21, the three terminal wires 52, 53 and 54 are passed through the opening 23 so as to be exposed within the chamber 38. The casing 11 is then mounted upon the guide rail structure, and the conduit 44 is connected with the casing 11 by means of the bushing 42. Meanwhile, the guide rail switch has been attached to the same section of the guide rail structure so that this conduit may also be connected with the switch box. The wires 55, 56, 57 and 58 are then run from the chamber 38 to the switch box, and the proper connections made at the switch box. The other ends of two of these wires 55-56 are then spliced to two of the motor terminal wires. The cap 45 is then secured to the casing 11 to close the housing 38, and the guide rail structure with the fit-

ting attached is ready for shipment to the job.

When installing the job, no attention by the erectors is required, so far as the operator mechanism is concerned. When the rail section carrying the fitting is properly located in relation to the door opening, and secured in position, the operator mechanism is assembled in the structure. It is necessary, however, for the electricians to install the main feed line conduits through the shaft adjacent each guide rail structure, and extending from a casing 11 at one door opening, to the casing 11 at the next door opening, throughout the shaft. The wires 49, 50 and 51 are then pulled through all of the conduits, each of the wires passing along the channel 36 through the opening 37 and throat 48 into the chamber 38, sufficient slack being allowed in the wires to permit the connection therewith of one of the motor terminals 52 and two of the wires 57 and 58 running through the conduit 44, with these main line wires at each fitting.

When these connections have been made, the work upon the fittings is complete. In fact, while on the job, the only work in connection with the motor installation is the running of the feed lines in the manner described, and the making of three electrical connections at each fitting. All other work may be completed in the shop where none of the inconveniences present while working in an elevator shaft are present.

A fitting embodying the invention, including the motor and the sheave, can be made of very much less weight than would be possible with any other arrangement. The conduits afford a certain degree of support to the casing 11, although the bolts connecting same with the guide rail structure are mainly relied upon.

In a fitting, all of the essential parts of the operator element are compactly arranged and provision is made by which that small part of the work of installation of the operator which must be done in the elevator shaft may be quickly and conveniently done. At the same time, the fitting affords all those safeguards required by various building departments or local ordinances, so far as the wiring of the installation is concerned.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A power fixture for elevator door operators embodying therein a narrow casing recessed at one edge thereof to form a pocket, having a front opening and a bottom opening, a sheave having a gear attached thereto, means whereby said sheave and said gear are

mounted in the side walls of said pocket, said gear and sheave projecting through said front opening, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheaves, a cap closing said motor recess, and means whereby said casing may be attached to the guide rail structure for elevator doors.

2. A power fixture for elevator door operators embodying therein a narrow casing recessed at one edge thereof to form a pocket, having a front opening and a bottom opening, a sheave having a gear attached thereto, means whereby said sheave and said gear are mounted in the side walls of said pocket, said gear and sheave projecting through said front opening, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheave, a cap closing said motor recess, said casing having a chamber adjacent the bottom thereof below said recess forming flange, means positioned above said pocket whereby an electric conduit may be attached to the casing, said casing having a channel rearwardly of said pocket extending from said last named means to said chamber, a plurality of means whereby electric conduits may be connected with the casing in communication with said chamber, and means whereby said casing may be attached to the guide rail structure for elevator doors.

3. A power fixture for elevator door operators embodying therein a narrow casing recessed at one edge thereof to form a pocket, having a front opening and a bottom opening, a sheave having a gear attached thereto, means whereby said sheave and said gear are mounted in the side walls of said pocket, said gear and sheave projecting through said front opening, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheave, a cap closing said motor recess, said casing having a chamber at the bottom thereof below said recess forming flange, means positioned above said pocket whereby an electric conduit may be attached to the casing, said casing having a channel rearwardly of said pocket extending from said last named means to said chamber, a plurality of means whereby electric conduits may be connected with the casing in communication with said chamber, said chamber opening outwardly on the same side of the casing as said pocket is located, a removable closure cap for said chamber, and means whereby said casing may be attached to the guide rail structure for elevator doors.

6. A power fixture for elevator door operators embodying therein a narrow casing recessed at one edge thereof to form a pocket,

with said chamber, and means whereby said casing may be attached to the guide rail structure for elevator doors.

4. A power fixture for elevator door operators embodying therein a narrow casing recessed at one edge thereof to form a pocket, having a front opening and a bottom opening, a sheave having a gear attached thereto, means whereby said sheave and said gear are mounted in the side walls of said pocket, said gear and sheave projecting through said front opening, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheave, a cap closing said motor recess, said casing having a chamber at the bottom thereof below said recess forming flange, means positioned above said pocket whereby an electric conduit may be attached to the casing, said casing having a channel rearwardly of said pocket extending from said last named means to said chamber, a plurality of means whereby electric conduits may be connected with the casing in communication with said chamber, and means whereby said casing may be attached to the guide rail structure for elevator doors.

5. A power fixture for elevator door operators embodying therein a narrow casing recessed at one edge thereof to form a pocket, having a front opening and a bottom opening, a sheave having a gear attached thereto, means whereby said sheave and said gear are mounted in the side walls of said pocket, said gear and sheave projecting through said front opening, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheave, a cap closing said motor recess, said casing having a chamber at the bottom thereof below said recess forming flange, means positioned above said pocket whereby an electric conduit may be attached to the casing, said casing having a channel rearwardly of said pocket extending from said last named means to said chamber, a plurality of means whereby electric conduits may be connected with the casing in communication with said chamber, said chamber opening outwardly on the same side of the casing as said pocket is located, a removable closure cap for said chamber, and means whereby said casing may be attached to the guide rail structure for elevator doors.

6. A power fixture for elevator door operators embodying therein a narrow casing recessed at one edge thereof to form a pocket,

having a front opening and a bottom opening, a sheave having a gear attached thereto, whereby said sheave and said gear are mounted in the side walls of said pocket, said gear and sheave projecting through said front opening, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheave, a cap closing said motor recess, said casing having a chamber at the bottom thereof below said recess forming flange, means positioned above said pocket whereby an electric conduit may be attached to the casing, said casing having a channel rearwardly of said pocket extending from said last named means to said chamber, a plurality of means whereby electric conduits may be connected with the casing in communication with said chamber, said chamber opening outwardly on the same side of the casing as said pocket is located, a removable closure cap for said chamber, said cover having an offset throat communicating with said channel whereby wires may be led from said channel into said chamber, and an offset hollow portion adjacent and below the front wall of the casing below said pocket, and means whereby said casing may be attached to the guide rail structure for elevator doors.

7. A power fixture for elevator door operators embodying therein a narrow casing recessed at one edge thereof to form a pocket, having a front opening and a bottom opening, a sheave having a gear attached thereto, means whereby said sheave and said gear are mounted in the side walls of said pocket, said gear and sheave projecting through said front opening, said casing having a guard flange at one side of the front opening of said pocket, and a curved shield projecting therefrom with a downward trend above said pocket, a circular recess forming flange upon the other side of said casing, a wall between said recess and said pocket having an opening adjacent the perimeter of said gear, a circular motor in said recess having its shaft projected through said opening, a gear carried by said shaft and enmeshed with the gear upon said sheave, a cap closing said motor recess, and means whereby said casing may be attached to the guide rail structure for elevator doors.

8. A power fixture for elevator door operators embodying therein a narrow casing recessed at one edge thereof to form a pocket, having a front opening and a bottom opening, a sheave having a gear attached thereto, means whereby said sheave and said gear are mounted in the side walls of said pocket, said gear and sheave projecting through said front opening, a circular recess forming flange upon the other side of said casing, a

wall between said recess and said pocket having an opening adjacent the perimeter of said gear, said casing having a guard flange projecting from the wall between said recess and said pocket, and a curved shield projecting from said casing with a downward trend adjacent the top of said front opening, a circular motor in said recess having its shaft projected through said opening, a gear carried by said shaft and enmeshed with the gear upon said sheave, a cap closing said motor recess, said casing having a chamber at the bottom thereof below said recess forming flange, means positioned above said pocket whereby an electric conduit may be attached to the casing, said casing having a channel rearwardly of said pocket extending from said last named means to said chamber, a plurality of means whereby electric conduits may be connected with the casing in communication with said chamber, said chamber opening outwardly on the same side of the casing as said pocket is located, a removable closure cap for said chamber, said cover having an offset throat communicating with said channel whereby wires may be led from said channel into said chamber, and an offset hollow portion adjacent and below the front wall of the casing below said pocket, and means whereby said casing may be attached to the guide rail structure for elevator doors.

In witness whereof I have hereunto affixed my signature, this 29th day of December, 1930.
